US00D881901S

(12) **United States Design Patent** (10) **Patent No.:** **US D881,901 S**
Nanjappan (45) **Date of Patent:** **** Apr. 21, 2020**

(54) **DISPLAY SCREEN OR PORTION THEREOF WITH GRAPHICAL USER INTERFACE**

(71) Applicant: **Otis Elevator Company**, Farmington, CT (US)

(72) Inventor: **Ezhil Nanjappan**, Farmington, CT (US)

(73) Assignee: **OTIS ELEVATOR COMPANY**, Farmington, CT (US)

(**) Term: **15 Years**

(21) Appl. No.: **29/646,807**

(22) Filed: **May 7, 2018**

Related U.S. Application Data

(63) Continuation of application No. 29/646,770, filed on May 7, 2018.

(51) **LOC (12) Cl.** **14-04**

(57) **CLAIM**

The ornamental design for a display screen or portion thereof with graphical user interface, as shown and described.

DESCRIPTION

The FIGURE is a front view of a display screen portion thereof with graphical user interface showing my new design.

The outermost broken-line perimeter illustrates a display screen or portion thereof and forms no part of the claimed design, The remaining broken lines illustrate portions of the graphical user interface and form no part of the claimed design.

1 Claim, 1 Drawing Sheet
